BOLT-ACTION FIREARM

Carl G. Swebilius, Hamden, Conn., assignor to
 Western Cartridge Company, New Haven,
 Conn., a corporation of Delaware

Application September 16, 1939, Serial No. 295,188

2 Claims. (Cl. 42—17)

This invention relates to improvements in bolt-action firearms and relates more particularly to a construction and arrangement of parts whereby a breech-bolt and its associated parts are retained in place in the structure.

One of the objects of the present invention is to provide a superior bolt-action firearm in which is combined reliability and strength with ease of assembly, disassembly and low cost for manufacture.

Another object of the present invention is to provide a bolt-action firearm having a superior construction and arrangement of parts whereby the breech-bolt may be laterally installed in and removed from a receiver.

A further object of the present invention is to provide a bolt-action firearm having a superior construction and arrangement of parts for controlling the action of the firing-member of the firearm.

Still another object is to provide a bolt-action firearm having a superior arrangement of parts for ejecting fired cartridges.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of a bolt-action firearm embodying the present invention:

Fig. 2 is a broken view partly in vertical central-longitudinal section and partly in side elevation of the central portion of the firearm;

Fig. 3 is a similar view but showing some of the parts more fully in section;

Fig. 4 is a transverse sectional view taken on the line 4—4 of Fig. 3;

Fig. 5 is a view mainly in side elevation and partly in central section of the receiver together with the rear portion of the barrel;

Fig. 6 is a view in side elevation of the unit comprising the breech-bolt, the bolt-carrier and associated parts;

Fig. 7 is a view thereof in front-end elevation but on a larger scale;

Fig. 8 is a top or plan view of the bolt-carrier detached, together with certain parts carried thereby;

Fig. 9 is a view in side elevation of the structure of Fig. 8;

Fig. 10 is a top or plan view of the breech-bolt detached, together with the parts carried thereby;

Fig. 11 is a view thereof in side elevation; and
 5 Fig. 12 is a view thereof in front-end elevation but on a larger scale.

The particular bolt-action firearm herein chosen for purposes of illustrating one form of the present invention, is of the automatic type, 10 that is to say, the discharge of one cartridge effects the extraction and ejection of the cartridge-case and causes the automatic insertion of a fresh cartridge. The firearm shown includes four major components, namely, a receiver 20, 15 a barrel 21, a stock 22 and a bolt-carrier 23.

The receiver 20 is cylindrically contoured exteriorly and is formed in its right-hand side wall adjacent its forward end with an ejection opening 24, and about midway of its length with a 20 longitudinal clearance-notch 25, and adjacent its rear end with a clearance-recess 26. The forward end of this said receiver 20 is interiorly threaded for the threaded connection of the exteriorly-threaded rear portion of the barrel 21, 25 which latter is provided with a usual cartridge-chamber 27.

Extending substantially throughout its length, 30 the receiver 20 is formed with a laterally- or downwardly-opening bolt-receiving chamber 28 having its upper half cylindrically contoured to conform to the similarly-contoured upper half of a reciprocating breech-bolt 29.

The breech-bolt 29 is retained in place in the bolt-receiving chamber 28 of the receiver 20 by 35 the bolt-carrier 23 before referred to. The main portion of the bolt-carrier 23 projects slightly upwardly into the lower portion of the bolt-receiving chamber 28 in the receiver 20 as is particularly well observable by reference to Figs. 3 and 4.

The bolt-carrier 23 above referred to, includes two substantially-corresponding and parallel side-plates 30 and 31 which are laterally spaced from each other to provide a central-longitudinal and vertical channel 32, by a rear spacing-block 33 and a front spacing-block 34. The upper portion of the rear spacing-block 33 projects above the upper surfaces of the respective side-plates 30 and 31 to form a head 35 which 45 conforms in cross-sectional form to the transverse form of the bolt-receiving chamber 28 in the receiver 20. The said head 35 of the rear spacing-block 33 is formed with a rearwardly-projecting coupling-extension 36 which fits into 50 a coupling-recess 36a formed in the forward face 55 of the front spacing-block 34.

of the rear wall 37 of the receiver 20. The said coupling-extension 36 overhangs a forwardly-extending coupling-lip 38 projecting forwardly from the lower portion of the said rear wall 37. As thus constructed, the said coupling-extension 36 and the coupling-lip 38 serve to normally prevent the downward movement of the rear portion of the bolt-carrier 23 with respect to the bolt-receiving chamber 28 in the receiver 20.

To releasably couple the forward portion of the bolt-carrier 23 to the receiver 20, the front spacing-block 34 is formed with a forwardly-opening recess or coupling-socket 39 which is adapted to receive the cylindrically-contoured rear end 40 of a coupling-screw 41. The said coupling-screw 41 is threadedly mounted in a block-like stock-attaching lug 42 (Figs. 2 and 3) depending from the rear portion of the barrel 21 and fixedly attached thereto by means of a dovetail connection 43.

The stock-attaching lug 42 has vertically threaded into it, the threaded upper end of a stock-attaching screw 44 which extends upwardly from the under face of the stock 22 through an escutcheon 45 mounted therein. The said stock-attaching screw 44 serves to secure the forward portion of the stock 22 to the barrel 21 and hence to the receiver 20 and its associated parts, with capacity for ready detachment.

As will be seen particularly well by reference to Figs. 4, 7 and 12, the breech-bolt 29 is formed on each of its respective opposite sides with one of two similar downwardly-facing longitudinal bearing-surfaces 46 and 47 respectively adapted to ride upon the respective upper faces of the side-plates 30 and 31 of the bolt-carrier 23. At its rear the said breech-bolt 29 is formed with a depending longitudinally extending guide-lug 48 which fits into the upper portion of the channel 32 in the said bolt-carrier 23 to engage the respective inner faces of the side-plates 30 and 31 with a free sliding fit.

The breech-bolt 29 is provided with a longitudinal passage 49 in which reciprocates a firing-plunger or firing-member 50 formed at its forward end with a firing-point 51 adapted to impinge against and fire a cartridge in the cartridge-chamber 27 of the barrel 21 in the usual manner of firearms. In its upper face adjacent its rear end, the firing-plunger 50 is formed with a forwardly-facing cocking-abutment 52 which is adapted to be releasably engaged by a sear-nose 53 located at the forward end of a pivotal sear 54 shown particularly well in Fig. 3. The sear 54 is mounted for pivotal movement in a vertical plane upon a transverse sear-pin 55 carried by and extending transversely of the head 35 of the rear spacing-block 33 across a recess 56 formed therein. The rear end of the sear 54 is pressed upwardly to effect the depression of its sear-nose 53, by means of a helical sear-spring 57 located in an upwardly-opening pocket 58 formed in the head 35 of the rear spacing-block 33.

Intermediate the sear-nose 53 and the sear-pin 55, the sear 54 is formed with a downwardly-facing actuating-abutment 59 which is adapted to be engaged by the upper end of the body-portion 60 of a T-shaped transmitting-member 61. The said transmitting-member 61 may be conveniently formed of sheet metal and is yieldingly pressed downwardly by a helical spring 62, as is especially well shown in Fig. 3. The said transmitting-member is mainly accommodated in a

clearance-passage 63 formed in the head 35 and extending vertically from the recess 56 downwardly to and through to the under face of the rear spacing-block 33. Adjacent the lower end of its body-portion 60, the transmitting member 61 is formed with a vertically-extending slot 64 through which extends a pin 65 mounted in the spacing-block 33 and serving to limit the vertical reciprocating movement of the said transmitting-member and to provide a fulcrum about which the same may rock.

The transmitting-member 61 in addition to its body-portion 60, includes a forwardly-extending finger 66 projecting from the said body-portion 60 about midway the height thereof and having its forward end beveled to provide a forwardly-and-upwardly-sloping cam-surface 67. The cam-surface 67 of the finger 66 is engageable by a similarly-sloping disconnecting-cam 68 formed at the rear end of a longitudinal clearance-passage 69 in the guide-lug 43 depending from the breech-bolt 29. When the breech-bolt 29 is moved rearwardly, the coaction of the cam 68 with the cam-surface 67 will rock the transmitting-member 61 in a counterclockwise direction to thus shift the upper end of the body-portion 60 to the rear of the actuating-abutment 59 of the sear 54. With the parts thus shifted, the sear 54 cannot be released by the actuation of the trigger of the firearm.

The under edge of the body-portion 60 of the transmitting-member 61 is adapted to be engaged and lifted by the upper end of a trigger-unit generally designated by the reference character 70, and which includes a tubular-portion 71 from the lower end of which latter extends a fingerpiece 72 projecting below the under surface of the stock 22 and into a space defined by a trigger-guard 73 secured to the under face of the said stock. The main portion of the trigger 70 is accommodated in a vertical clearance-passage 74 formed in the stock 22 and intersected at its forward end by an upwardly-and-forwardly-sloping passage 75 which, in turn, intersects at its forward upper end an upwardly-opening longitudinally-extending pocket 76 formed in the upper face of the stock 22.

The upper portion of the tubular portion 71 on the trigger 70 is provided with a forwardly-and-upwardly-sloping arm 77 having its forward end extending around a pivot-pin 78 arranged crosswise of the stock 22 and carried thereby and constituting a fulcrum about which the trigger-unit 70 swings.

The tubular portion 71 of the trigger-unit 70 has passing therethrough a tubular magazine-housing 79 which also passes through the passage 75 in the stock 22 and has its open forward end entered into the vertical and longitudinally-extending channel 32 in the bolt-carrier 23, as will be apparent by reference to Fig. 3 in particular. The said magazine-housing extends forwardly from the butt-end of the stock 22 and encloses a magazine-tube 80 having a usual spring-pressed cartridge-follower 81 therein. The said cartridge-follower yieldingly presses forwardly upon the rearmost one of a column of cartridges which may be located in the said magazine-tube and also such of those cartridges as may be in process of being fed toward the cartridge-chamber 27.

Returning now to the breech-bolt 29 and the firing-plunger 50, it will be noted by reference to Fig. 3 in particular that the said firing-plunger is formed with an axial rearwardly-opening bore 82 receiving the forward portion of a helical

firing-spring 83 thrusting at its forward end against the end wall of the bore 82 in the said firing-plunger. At its rear end, the firing-spring 83 encircles the relatively-slender forward portion of a spring-guiding plunger 84 seated at its rear end against the forward face of the head 35 of the rear spacing-block 33. The said plunger 84 is formed with a forwardly-facing spring-seat 85 against which is seated the rear end of the firing-spring 83. The said spring-guiding plunger 84 together with the rear portion of the firing-spring 83 is adapted to be telescopically received in the bore 82 in the firing-plunger 50 when the latter is moved rearwardly from the position in which it is shown in Fig. 3.

For the purpose of yieldingly urging the breech-bolt 29 forwardly into its breech-closing position, a helical breech-closing spring 86 is provided, the forward portion of which is housed in a bore 86a formed in the said breech-bolt. The said spring 86 presses at its forward end against the end wall of the bore 86a in the breech-bolt 29, as shown in Fig. 10. The said breech-closing spring 86 encircles a spring-guiding plunger 87 which at its rear end, like the rear end of the breech-closing spring 86, presses against the front face of the head 35 of the rear spacing-block 33.

For the purpose of locking the transmitting-member 61 against upward movement to operate the sear 64 and thus release the firing-plunger 50, a safety-lock is provided which comprises a cylindrical stem 88 and a lever-like fingerpiece 89. The said stem 88 extends transversely across the rear portion of the bolt-carrier 23 and is journaled therein for oscillating movement while the fingerpiece 89 extends above the adjacent portion of the stock 22 and is accommodated in the shallow clearance-recess 26 before described in the right side face of the receiver 20 near the rear end thereof. At a point in line with the body-portion 60 of the transmitting-member 61, the stem 88 of the safety-lock is formed with a clearance-notch 90 which normally permits the free vertical reciprocation of the transmitting-member 61 when said stem is in the position in which it is indicated in Fig. 3 and its fingerpiece 89 is in the position in which it is shown by full lines in Figs. 1 and 2. When, however, the fingerpiece 89 is turned rearwardly into the position in which it is indicated by broken lines in Fig. 2, the stem 88 will be similarly turned in a counterclockwise direction to thereby extend a portion of the said stem into the upward path of movement of the stop-shoulder 91 of the transmitting-member 61, to thus prevent the upward lifting movement of the said transmitting-member by the trigger-unit 10. In this manner the firearm is rendered safe since it cannot be discharged under the conditions just referred to.

Installed in the forward portion of the channel 32 in the bolt-carrier 23, is a group of parts constituting what is commonly referred to in the art as a "magazine-throat" and related parts, as will now be described.

The magazine-throat above referred to, includes two laterally-spaced apart complementary side-plates 92 and 93 (Fig. 8) respectively located against the respective inner faces of the side-plates 30 and 31 of the bolt-carrier 23.

Rigidly mounted between the upper rear portions of the respective side-plates 92 and 93 of the magazine-throat, is a cut-off carrier 94 secured to the bolt-carrier 23 by any suitable means such, for instance, as transverse pins 95-96

5 seen by reference to Fig. 3.

10 Located laterally intermediate and extending parallel with the side-plates 92 and 93 of the magazine-throat, is a cartridge-elevating plate 98 having substantially the shape of a right-angle triangle and having its hypotenuse sloping upwardly and forwardly away from the open end of the magazine-tube 80 in substantial parallelism therewith. The said cartridge-elevating plate 98 is secured in place by lateral pins 99-99 which 15 also extend into the side-plates 30 and 31 of the bolt-carrier 23.

15 The cartridge cut-off 96, above referred to, is formed at its forward end with an actuating-nose 100 which is adapted to project upwardly through a clearance-opening 101 in the cut-off carrier 94 for engagement with the underside of the breech-bolt 29 for entry on occasion into a clearance-notch 102 formed in the underside of the said breech-bolt, as shown particularly well in Fig. 3.

20 The cartridge cut-off 96 is formed about mid-way of its length on its underside with a downwardly-projecting cartridge-stopping finger 103 which is adapted to be sequentially engaged by the forward face of the rims 104 of cartridges such as 105, 106 and 107 shown in Fig. 3, and also the rims of such other cartridges as may be included in a column of cartridges, as the same, in turn, pass out of the forward end of 25 the magazine-tube 80.

25 The rear spacing-block 33, before referred to, is rigidly organized with the side-plates 30 and 31 of the bolt-carrier 23 by two (more or less) transverse coupling-pins 108 and 109, as is shown 30 in the drawings. Similarly, the front spacing-block 34 is rigidly organized with the said side-plates 30 and 31 by means of coupling-pins 110 and 111, as is shown particularly well in Figs. 3, 6 and 9.

35 Immediately below the integral rear wall 37 of the receiver 20, the stock 22 has extending thereacross a stock-attaching pin 112 which is adapted to fit in a rearwardly-opening transverse stock-attaching notch 113 formed in the lower portion of the rear spacing-block 33 of the bolt-carrier 23.

40 Secured to the left-hand side-plate 31 of the bolt-carrier 33 is a cartridge-ejector 114 of L-shaped form in cross-section and comprising a vertical leg 115 and a substantially-horizontal flange-like leg 116. The vertical leg of the said cartridge-ejector is suitably recessed into a vertical groove provided in the outer face of the side-plate 31, and the horizontal leg 116 thereof projects inwardly toward the center of the breech-bolt 29. The breech-bolt 29 is provided in its left-hand side-wall with a longitudinal clearance-groove 117 for the accommodation of the said horizontal leg 116 of the cartridge-ejector 114. Adjacent its rear end, the horizontal leg 116 of the cartridge-ejector 114 is provided with a forwardly-facing ejecting-abutment 118 which is adapted to be engaged by the rear faces of empty cartridges-cases as the same are pulled rearwardly by means of an extractor 119 carried 45 at the forward end of the breech-bolt 29.

50 The breech-bolt 29 may be moved rearwardly by the force exerted by the firing of a cartridge, or the said breech-bolt may be manually moved rearwardly by means of a bolt-handle 120 pro-

jecting from its right side wall and accommodated in the clearance-notch 25 in the side wall of the receiver 20.

Beyond the functions above indicated for the various parts, it is unnecessary to describe in detail the operation of the firearm other than phases thereof with which the present invention is mainly concerned.

As has before been pointed out, the breech-bolt 29 is retained in place against downward displacement within the hollow receiver 20 by the bolt-carrier 23, which latter provides convenient and accurate bearing-surfaces for guiding the said breech-bolt in its reciprocating movements.

Should it be desired for any reason to remove the breech-bolt 29 from the receiver 20, the stock 22 is first detached by unscrewing the stock-attaching screw 44 from the stock-attaching lug 42 depending from the barrel 21, and then rocking the said stock with respect to the still unitary receiver 20, barrel 21, and bolt-carrier 23, about the stock-attaching pin 112 as a center. When the parts have been sufficiently rocked, the stock 22, together with its stock-attaching pin 112, may be drawn rearwardly so as to disengage the said stock-attaching pin from the stock-attaching notch 113 in the rear face of the rear spacing-block 33.

The next step in demounting the firearm may be accomplished by backing the rear end 40 of the coupling-screw 41 out of the coupling-socket 39 in the front spacing-block 34 of the bolt-carrier 23. The forward end of the bolt-carrier 23 may now be rocked downwardly with respect to the receiver 20 and the barrel 21, until the said front end is completely withdrawn from the downwardly-opening bolt-receiving chamber 28 in the said receiver 20. The bolt-carrier may now be slid forwardly along a downwardly-inclined path until the under face of the coupling-extension 36 of the head 35 of the rear spacing-block 33 clears the coupling-lip 38 extending forwardly from the lower edge of the rear wall 37 of the receiver 20. In this manner, the entire assembly illustrated particularly well in Figs. 6 and 7 may be removed as a whole from the receiver 20. The breech-bolt and its associated parts may now be removed as a unit from the bolt-carrier 23, so that the said breech-bolt and associated parts assume the appearance shown in Figs. 10 and 11, and the bolt-carrier 23 and associated parts present the appearance shown in Figs. 8 and 9.

To re-assemble the firearm, the steps above described may be reversed, as will be obvious.

By the construction and organization of parts above described, the rear portion of the receiver 20 may be made solid and integral, to thus provide maximum strength and the breech-bolt 29 firmly held in place in the said receiver and ac-

curately guided by the bolt-carrier 23, thus minimizing complex machining operations within the said receiver 20 and permitting an entire assembly, such as illustrated in Figs. 6 and 7, to be assembled together and tested prior to their introduction into the relatively inaccessible interior of the receiver 20.

Furthermore, by organizing the cartridge-ejector 114 with the bolt-carrier 23 or its equivalent, an extremely rugged ejector may be provided which will withstand continued hard usage without derangement.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A bolt-action firearm including in combination: a receiver having a laterally-opening bolt-receiving chamber; a breech-bolt having a longitudinal clearance-groove and reciprocatable in the bolt-receiving chamber of the said receiver; a removable bolt-carrier having a guideway along which the said breech-bolt slides and removably secured to the said receiver in position to hold the said breech-bolt in the bolt-receiving chamber of the said receiver and to guide the said breech-bolt for movement therein; and a cartridge-ejector of L-shaped form having one leg attached to the said bolt-carrier and having a second leg fitting into the longitudinal clearance-groove in the said breech-bolt.

2. A bolt-action firearm including in combination: a receiver having a downwardly-opening bolt-receiving chamber and a substantially-closed rear wall; a breech-bolt reciprocatably mounted in the bolt-receiving chamber of the said receiver and dimensioned to be laterally introduced into and removed therefrom; a removable bolt-carrier comprising a pair of laterally-spaced-apart side-plates, each having an upwardly-facing guideway for the said breech-bolt, and providing between them a vertical channel through which cartridges may be fed, a spacing-block projecting upwardly from the rear portion of the said side-plates into position to be interposed between the rear end of the said breech-bolt and the rear wall of the said receiver, the said bolt-carrier being removably secured to the said receiver in position to hold the said breech-bolt in the bolt-receiving chamber of the said receiver; and a cartridge-ejector carried by one of the side-plates of the said bolt-carrier and removable from the said receiver as a unit with the said bolt-carrier.

CARL G. SWEBILIUS.
